UNITED STATES PATENT OFFICE

1,940,575

FUSE SWITCH

Lester Pierce Boll, University City, Mo., assignor
to W. N. Matthews Corporation, St. Louis, Mo.,
a corporation of Missouri

Application November 21, 1932
Serial No. 643,665

4 Claims. (Cl. 200—126)

This invention relates to fuse switches, and with regard to certain more specific features, to reclosing fuse switches.

Among the several objects of the invention may be noted the provision of an improvement upon the structure disclosed in the United States patent application of Ralph Pittman et al., Serial Number 602,666, filed April 2, 1932, now United States Patent Number 1,894,056, dated January 10, 1933 for Automatic fuse-changer; the provision of apparatus of the class described incorporating by combination, the structures disclosed in the United States patent application of Theodore Birkenmaier, Serial Number 575,193, filed 15 November 16, 1931, now United States Patent Number 1,935,386, dated November 14, 1933 for Fuse and United States Patent 1,899,915 issued to C. L. Matthews et al. on February 28, 1933 for Electrical cut-out; the provision of apparatus of 20 the class described which employs identical fuse cartridge for reloading any of its elements; the provision of apparatus of this class whose elements shall be easily changeable and the conditions of which are readily visible without close 25 inspection; and the provision of apparatus of the class described which is simple in operation, and compact, rugged and economical in construction. Other objects will be in part obvious and in part pointed out hereinafter.

30 The invention accordingly comprises the elements and combinations of elements, features of construction, and arrangements of parts which will be exemplified in the structures hereinafter described, and the scope of the application of 35 which will be indicated in the following claims.

In the accompanying drawings, in which is illustrated one of various possible embodiments of the invention,

Fig. 1 is a side elevation of the apparatus;

40 Fig. 2 is a front elevation viewed from the right of Fig. 3;

Fig. 3 is a plan view viewed from the top of Fig. 2;

Fig. 4 is an enlarged detail of the upper end 45 of a fuse cartridge;

Fig. 5 is a plan view of Fig. 4; and,

Fig. 6 is an enlarged detail of the lower end of said cartridge in a pivoting socket; the latter being in thrown position.

50 Similar reference characters indicate corresponding parts throughout the several views of the drawings.

Referring now more particularly to Fig. 1, there is shown at numeral 1 an insulator rack 55 supporting insulators 3, the latter carrying up-

per and lower brackets 5 and 7 respectively. A line wire connection 9 is provided on the upper bracket 5 and line wire connections 11 on the lower bracket 7. Either one of the line connections 11 may be used, as illustrated in Fig. 2 which shows the left one in use.

The brackets 5 and 7 carry centrally located spring terminal clips 13 and 15 for spring engagement with the flat side of upper and lower terminal contacts 17 and 19 respectively of a central fuse cartridge C. This cartridge C is of a general nature of the cartridge described in said Birkenmaier application, and has a connection 21 in the upper contact 17 for a fuse link 23 which passes downwardly through an insulating tube 25 of said cartridge C and emerges from the lower end thereof. The insulated tube 25 passes through the lower contact 19.

Exteriorly, the fuse link 23 passes under and over a hinged element 29 of a clamp 27, a leaf spring element 31 forming the other element of the clamp as described in said Patents 1,935,386 and 1,899,915 (see also Fig. 2).

When the link 23 is loaded, the spring 31 is pulled down from the untensioned, dotted-line position also shown by the numeral 31 in Fig. 1, and the clamp 27 is opened by rotating the member 29 clockwise and thereafter feeding in the end of the link 23. Then upon release of the link from the hand of the operator, the strained position is assumed as shown in solid lines in Fig. 1. The spring 31 forces down the element 29, thus closing the clamp 27 to hold the link 23 in strained position in the tube. These points will be clear from Figs. 1 and 2 and from said Birkenmaier application.

The upper end of the leaf spring 31 is fastened to a platen 33 which is hinged to the lower contact 19 and which is normally pressed upwardly by a leaf spring 35 reacting against the contact 19. The leaf spring 35 is shown also in Fig. 6.

Said lower contact 19 also carries a downward extension 37 carrying trunnions 39 which rest in open sockets 41 of rigid extended ears 43 of the central portion of the lower bracket 7 (Fig. 1). The sockets 41 being open at the top, provision is thereby made for applying and removing as a whole the central fuse cartridge C.

Referring now to the upper terminal 17 of the cartridge C (Fig. 5 shows an identical cartridge L), it will be seen to include ears 45 for pivotally supporting a bell crank 47, the latter having a latch arm 49 and a pressure arm 51, the latter being engaged by either corner 53 or 55 of a rocker 57 having an operating rim 59. A leaf spring 61

reacting between the upper terminal 17 and the arm 51 of the bell crank 47 tends to normally throw the latch 49 into upward position. However, if a hook of a lineman's extension tool or the like is applied to the ring 59, either upward or downward pressure (in fact any pressure except one directed into the axis of rotation of the member 57) will cause either one of the corners 53 or 55 to press the arm 51 of the bell crank 47, thus causing the latch 49 to be depressed against the reaction of said spring 61. The use of this feature will be particularized hereinafter.

The cartridge C (as well as identical cartridges L and R, to be referred to) may be provided with the fuse link 23, the same being tensioned by the spring 31 while the cartridge as a whole is separated from the terminals 13 and 15. Thus loaded, the cartridge C may have the trunnions 39 applied to the fixed sockets 41, the whole cartridge then being rotated to a vertical position (Fig. 1), the upper terminal 17 engaging the upper line terminal 13.

The lower bracket 7 also carries sidewardly located sets of ears 63 which pivotally support socket members 65 for receiving the trunnions 39 of right- and left-hand cartridges R and L respectively (see Figs. 1, 2 and 6), said cartridges R and L being exact duplicates of said central cartridge C.

The pivoted sockets 65 have upward socket extensions 67 between which, and sockets 69 on the bracket 7, are positioned compression coil springs 71 which tension the socket members 65 when said members 65 are rotated counterclockwise (Fig. 1). Latches 73 and 75 hold the pivoted socket members 65 of the cartridges L and R respectively against clockwise rotation after they have been rotated counterclockwise against the reactions of springs 71.

As shown in Fig. 1, no upper terminal spring clips are provided for the cartridges R and L in their counterclockwise or vertical positions. Such spring terminal clips are provided at the ends of a branch 79 of an extending arm 77, and in the planes of the respective planes of the cartridges R. These clips are numbered 81 and 83 for the respective cartridges L and R.

The lateral extension 79 also carries U-shaped members 85 and 87 which clear the upper ends of the cartridges L and R and which are provided with stops 89 and 91 respectively for preventing rocketing of the cartridges because of reactions engendered upon blowing of the same. The U-shaped members 85 and 87 also have lower edges 93 which are adapted to be engaged by the ends 49 of the arms 49 upon forward swing of the cartridges R and L (Fig. 1).

Referring again to the lower bracket 7, releasing means for the cartridges R and L will now be described. The left-hand latch 73 is carried on a rock shaft 95 supported in bearings 97 on the lower bracket 7. Said rock shaft 95 has an extending arm 99 which is adapted to be engaged by an extension 101 of the central cartridge platen 33 when the latter lifts (as when the fuse switch 23 blows, thus permitting release of the spring 31 which moves upwardly through the dotted-line position shown in Fig. 1). Under these conditions the leaf spring 35 lifts the platen 33 with its arm 101 to contact with the extension 99 and thus, through the rock shaft 95 and latch 73 to release the terminal socket 65 of the left-hand cartridge L.

On the other hand, the latch 75 is carried on a rock shaft 103 supported in bearings 105 on

said lower bracket 7. Said rock shaft 103 carries an extending arm 107 which is adapted to be contacted by a lateral extension 109 of the platen 33 of said left-hand fuse cartridge L. Thus when the left-hand fuse blows, its spring 31 moves upwardly so that its platen 109 contacts the extension 107 to rotate the latch 75 so as to release the right-hand fuse cartridge R.

When the left- and right-hand fuse cartridges are released respectively, the respective springs 71 force them counterclockwise to dotted-line position shown in Fig. 1. In this position the latch arms 49 have contacted with the edges 93, and the upper contacts of said cartridges are positioned within the respective clips 81 and/or 83.

The operation of the device is as follows:

All of the cartridges C and R (being removed from the apparatus) are fused, the springs 31 taking the solid-line position shown in Fig. 1. The cartridges are then placed with trunnions 39 in their respective sockets. It will be understood that the socket 41 of the central cartridge C is rigid and that the sockets 65 of the lateral cartridges L and R are swingable, but that when the cartridges L and R are applied, they are held back by latches 73 and 75 against the reaction of spring 71.

All of the cartridges having been rotated counterclockwise to the solid line position shown in Fig. 1, the central cartridge C thus has its fuse placed across the line. The fuses of the right- and left-hand cartridges are not so placed, because the upper termini of the cartridges are not in contact with any line terminal clips.

The device is now in condition for operation. When the fuse of cartridge C blows, it is pulled from the tube 25 by the action of spring 31, and also by the expulsion action of the violent expansion of gases. It will be noted that the extension arm 77 functions as a stop for preventing substantial upward movement of the central cartridge C upon explosive reaction.

After the lower part of the link 23 is ejected and withdrawn from the tube 25, the clamp 27 automatically opens, thus to drop the fuse link to the ground and positively opening and clearing the circuit.

Also, the spring 31 moves upwardly through the dotted line position shown in Fig. 1, thus aiding the small leaf spring 35 to upwardly rotate the platen 33 of the cartridge C. This causes arm 101 (Fig. 2) to move upwardly to contact the extension arm 99, thus to rotate the rock shaft 95 and latch 73. This releases the pivoted socket 65 of said cartridge L, which, under the action of its spring 71 moves to the dotted line position shown in Fig. 1. In this position the upper terminal of the cartridge L contacts with the clip 81, the latch 49 limiting the movement by contact with the edges 93. This places the cartridge L in circuit after a short interval of open circuit condition.

If the trouble which causes the first fuse cartridge C to blow has cleared before the second fuse cartridge L moves into contact position, no further action takes place except that the second cartridge goes into action. However, if the trouble has not been cleared, the excessive current will be applied to the second cartridge L in circuit. Its link will also drop to the ground, according to the sequence of the events above described in connection with the first cartridge, and its spring 31 will cause its arm 109 to contact the arm 107, thus rotating the shaft 103 and

rotating the latch 75 to release the right hand cartridge R so that it springs to the dotted line position shown in Fig. 1. If the trouble has cleared, this cartridge will thereafter carry the 5 load, but if it has not, it also will blow.

Thus if the trouble on the line is temporary, either the second or third cartridge L or R will maintain service, but if the trouble is permanent, the line will be permanently open until a line 10 crew repairs the trouble.

Among the advantages of the invention may be noted the fact that the cartridges C, L and R are identical and it is therefore unnecessary to use any care in determining what fixed or rotatable socket a given cartridge shall be placed in. 15 Each cartridge fits in any position.

The lineman's hooked stick, when placed in the respective rings 59 may be pressed upwardly or downwardly to effect release of the latches 49 so that the cartridges may be removed. It will be noted in this connection that the latch 49 of the central cartridge C holds it in position by contact with edges 50 of the upper bracket 5.

A trouble man can see at a glance, even when 25 traveling in a motor car, or otherwise, whether any of the cartridges have blown and which ones have done so, and this by noting the angular positions of the cartridges or tubes. If cartridge L has been thrown outwardly, this means that 30 cartridge C has blown. If cartridges L and R are thrown outwardly, this means that at least both C and L have blown, and in any event that the next blowing of cartridge will be permanent and that no automatic refusing will occur, and 35 thus that a replacement is in order so that the effectiveness of the device as a repeating fuse may be restored.

If cartridges or tubes L and R are forward and 40 in their upper contacts, then for a short moment both C and L and/or C and R tubes are in circuit at the same time, if not blown. It is only necessary to push back the L and R cartridges to the vertical position out of their upper contacts to put all of the load on the link in the refuse tube 45 C. It will be understood that cartridges L and R are passed through their respective contacts 81 and 83 in making removals and replacements.

If the troubleman finds that C and L tubes are both without links, he removes both tubes and 50 relinks them. Then he puts one of them back in the vertical position and immediately pushes the other tube back to its vertical position.

If the troubleman finds that all of the tubes have cleared, he removes them with his stick and 55 after relinking them he puts any one of the re-linked tubes into the vertical position and then pushes the others through contacts to their vertical positions.

All of the latches and/or pawls are self-locking when the tubes are pushed into their vertical positions.

It is to be understood that the term "vertical" is herein to be construed as a position wherein the cartridges or tubes generally lie parallel to the position of the fixed central cartridge C, inasmuch as the device as a whole may be fastened to a vertically arranged member or one that is horizontal if desired. The device operates independently of the relative position of the same 70 with respect to the earth.

In view of the above, it will be seen that the several objects of the invention are achieved and other advantageous results attained.

As many changes could be made in carrying

out the above constructions without departing from the scope of the invention, it is intended that all matter contained in the above description or shown in the accompanying drawings shall be interpreted as illustrative and not in a 80 limiting sense.

I claim:

1. A reclosing fuse switch comprising line contacts, a plurality of fuse-containing insulating cartridges having contacts adjacent the ends thereof, the contacts of one of said cartridges engaging cooperating contacts to close a circuit, fuses electrically engaging contacts in said cartridges, platens pivoted to the other contacts of the cartridges, leaf springs attached to said platens and removably attached to the respective links to tension the same, said springs dropping the links after ejection upon the fuses blowing, said spring moving to new positions, and means responsive to the alternative positionings of said 90 spring adapted to actuate other of said tubes to engage cooperating contacts to close the circuit. 95

2. A reclosing fuse switch comprising line contacts, a plurality of fuse-containing insulating cartridges having contacts adjacent the ends 100 thereof, the contacts of one of said cartridges engaging cooperating contacts to close a circuit, fuses electrically engaging contacts in said cartridges, leaf springs swingingly attached respectively to each of one set of contacts and removably attached to the respective links to tension the same, said springs dropping the links after ejection upon the fuses blowing and moving to new positions, and means responsive to the alternative positionings of said springs adapted to 105 110 actuate other of said tubes to engage cooperating contacts to close the circuit.

3. A reclosing fuse switch comprising fixed and pivoted line contacts, a plurality of fuse-containing insulating cartridges having contacts adjacent the ends thereof, the contacts of one of said cartridges engaging cooperating fixed contacts to close the circuit, fuses electrically engaging contacts in said cartridges, leaf springs attached respectively to each of one set of contacts 115 and removably attached to the respective links to tension the same, said springs dropping the links after ejection upon the fuses blowing and moving to new positions, means responsive to the alternative positioning of said springs adapted to 120 125 actuate other of said cartridges to engage cooperating fixed contacts to close the circuit, said other tubes being in a plurality of said pivoted line contacts.

4. A reclosing fuse switch comprising fixed and pivoted line contacts, a plurality of fuse-containing insulating cartridges having contacts adjacent the ends thereof, the contacts of one of said cartridges engaging cooperating fixed line contacts to close a circuit, fuses electrically engaging contacts in said cartridges, platens pivoted to one set of contacts of the cartridges, leaf springs attached to said platens and removably attached to the respective links to tension the same, said springs dropping the links after ejection upon the fuses blowing and moving to new positions, and means responsive to the alternative positioning of said springs adapted to 130 135 140 145 actuate other of said cartridges which are in the pivoted line contacts to engage cooperating fixed contacts to close the circuit, said cartridges and parts mounted thereon being identical.

LESTER PIERCE BOLL.
